UNITED STATES PATENT OFFICE.

EDWARD DODSON, OF DEAL, ENGLAND.

CONSTRUCTION OF AERIAL IMPELLERS, PROPELLERS, OR FANS.

1,184,168.

Specification of Letters Patent. Patented May 23, 1916.

Application filed July 17, 1915. Serial No. 40,379.

To all whom it may concern:

Be it known that I, EDWARD DODSON, subject of the King of Great Britain, residing at No. 24 Queen street, Deal, in the county of Kent, England, have invented new and useful Improvements in the Construction of Aerial Impellers, Propellers, or Fans, of which the following is a specification.

This invention relates to improvements in the construction of aerial impellers, for use either as aerial propellers for propelling bodies through air, or as fans, such as are employed for creating a draft of air through the radiators of motor cars, and for other purposes.

According to the invention, the propeller or fan is built up of stampings from sheet metal, each stamping being in the shape of a propeller blade with a divided ring at its inner end, the portions of which ring at each edge of the blade being bent into different but approximately parallel planes, so that the assembled fan has a ring boss in front and behind built up by the respective portions of the divided rings of the blades, and interconnected by the oblique blades. The blades are secured in correct angular position by bolts passing through holes in the two ring bosses.

A fan and an aerial propeller constructed according to the invention are illustrated on the accompanying drawing, in which:

Figure 1 is a front elevation of a stamped blade for a fan before being bent. Fig. 2 is a front elevation of the stamped blade after being bent, and Fig. 3 is a corresponding plan. Fig. 4 shows a plurality of stamped and bent blades, nested together preparatory to being mounted on a shaft or sleeve. Fig. 5 is a front elevation, and Fig. 6 is a side elevation, one blade being in section taken along the line 6—6 of Fig. 5, showing four blades assembled and mounted on a sleeve. Fig. 7 is a front elevation of a finished blade for an aerial propeller. Fig. 8 is a transverse section taken along the line 8—8 of Fig. 7, and Fig. 9 is a transverse section taken along the line 9—9 of Fig. 7.

Referring to Fig. 1:—*a* is a blade for a fan stamped from a sheet of metal, having a ring portion *b* at its narrow end, divided at *b*¹ at a situation remote from the blade *a*, and with an oval aperture or eye, the major axis of which eye is transverse to the blade *a*.

As shown in Figs. 2 and 3, the two por-

tions of the ring *b* are bent into different but more or less parallel planes, so as to form incomplete ring bosses at each edge of the blade *a*. At the same time the eye is contracted to a circle so that the ends of the incomplete ring bosses *b* overlap.

A number of the blades *a* with their incomplete ring bosses *b* are nested together, as shown in Fig. 4, wherein four are illustrated, and are then threaded on a shaft or sleeve *q*, Figs. 5 and 6. After being mounted on the sleeve *c*, the blades *a* are separated angularly to equal distances apart, the root of each blade being overlapped in front and behind by the incomplete ring bosses *b* of the next blades, whereby the incomplete ring bosses *b*, together form complete ring bosses in front of and behind the fan, as shown in Figs. 5 and 6. The blades are then secured in correct relative angular position and also are secured to a flange *d* of the sleeve *c*, by means of bolts *e*, which are threaded through holes in the flange *d* and through holes, previously formed in appropriate positions in the ring boss portions *b* to coincide when assembled, and the bolts are secured by nuts *f*.

In a blade for an aerial propeller it is more important than in a blade for a fan, that both the front and rear surfaces of the blade conform to the contour found most appropriate for acting upon the air. For this reason the blade for an aerial propeller shown in Figs. 7—9 is built up of a pair of stampings, one *a*¹ being appropriately bent to provide the front surface, and the other *a*² being appropriately bent to provide the rear surface. The leading and trailing edges of the stampings *a*¹ and *a*² are riveted together. As, however, an undesirable hollow would be left alongside the leading edge of the front surface *a*¹, a strip of metal *g* is riveted between the leading edges of *a*¹ and *a*², and is bent back over the hollow to form a fairing for the stream lines of air. Similarly, but merely for strengthening purposes a strip of metal *h* is riveted between the trailing edges of *a*¹ and *a*² at their junction with the ring boss *b*.

i, *j* are distance or bridge pieces inserted between the two bent stampings *a*¹ and *a*².

The incomplete ring bosses *b* are the same as described with reference to Figs. 1—6, except that each portion consists of two thicknesses of sheet metal.

With a fan or aerial propeller constructed as above described, broken or deformed blades can easily be renewed.

The metal from which the blades and inserted pieces are stamped is preferably sheet aluminium, which material is harder and more durable than cast aluminium, but the blades may be stampings of other metals or alloys, such as steel.

10 I claim:

1. In an aerial impeller, a blade stamped and bent from sheet metal and an incomplete ring boss at both the leading and trailing edges of said blade.
- 15 2. In an aerial impeller, a blade stamped and bent from sheet metal and an incomplete ring boss at both the leading and trailing edges of said blade, said incomplete boss portions being approximately parallel and 20 their ends overlapping.
- 25 3. In an aerial impeller, a plurality of blades stamped and bent from sheet metal, an incomplete ring boss at both the leading and trailing edges of each said blade, and overlapping the root of the next blade assembled into approximately parallel complete ring bosses at the front and rear of 25 said aerial impeller.
- 30 4. In an aerial propeller, a blade composed of a pair of bent stampings from sheet metal secured together at their leading and trailing edges, a strip of sheet metal secured between the leading edges of said stampings and bent over the front of said blade and a 35 portion of a ring boss at both the leading and trailing edges of said blade.

5. In an aerial propeller, a blade composed of a pair of bent stampings from sheet metal secured together at their leading and trailing edges, a strip of sheet metal secured 40 between the leading edges of said stampings and bent over the front of said blade and a portion of a ring boss at both the leading and trailing edges of said blade, said boss portions being approximately parallel and 45 their ends overlapping.

6. In an aerial propeller, a plurality of blades each composed of a pair of bent stampings from sheet metal secured together at their leading and trailing edges, a strip of sheet metal secured 50 between the leading edges of each said pair of stampings and bent over the front of each said blade, a portion of a ring boss at both the leading and trailing edges of each said blade, assembled into approximately parallel complete ring bosses at the front and rear of 55 said aerial propeller.

7. A stamping for an aerial impeller, consisting of a portion stamped to the developed profile of a blade and at the inner end of said blade-shaped portion a divided ring portion with an oval aperture the major axis of which is transverse to said blade-shaped portion.

In testimony whereof I have signed my name to this specification in the presence of two subscribing witnesses.

EDWARD DODSON.

Witnesses:

ROBERT ARTHUR SMITH,
D. E. BRETELL.
